(57) **CLAIM**

The ornamental design for a movement sensor, as shown and described.

DESCRIPTION

FIG. 1 is a perspective view illustrating the movement sensor showing my new design;

FIG. 2 is a front view of the movement sensor shown in FIG. 1;

FIG. 3 is a rear view of the movement sensor shown in FIG. 1;

FIG. 4 is a first side view of the movement sensor shown in FIG. 1;

FIG. 5 is a second side view of the movement sensor shown in FIG. 1;

FIG. 6 is a top plan view of the movement sensor shown in FIG. 1; and,

FIG. 7 is a bottom plan view of the movement sensor shown in FIG. 1.

The broken lines in the FIGURES depict portions of the movement sensor that form no part of the claimed design.
